UNITED STATES PATENT OFFICE.

CARL GOLDMANN, OF NEW YORK, N. Y., ASSIGNOR OF ONE-HALF TO
ERNEST KEHR, OF NEW YORK, N. Y.

BOX-OPENER.

No. 809,050.

Specification of Letters Patent.

Patented Jan. 2, 1906.

Application filed June 6, 1905. Serial No. 264,022.

To all whom it may concern:

Be it known that I, CARL GOLDMANN, a subject of the German Emperor, and a resident of the city of New York, borough of 5 Manhattan, in the county and State of New York, have invented a new and Improved Box-Opener, of which the following is a full, clear, and exact description.

This invention relates to box-openers; and 10 it consists, substantially, in the details of construction and combinations of parts hereinafter more particularly described, and pointed out in the claims.

The invention has reference more especially 15 to openers for pasteboard or paper boxes—such, for instance, as are employed for containing ice-cream and the like in bricks or blocks—although applicable to other forms of boxes; and one of the principal 20 objects of the invention is to provide a device of this kind which is simple in its construction and comparatively inexpensive to manufacture, besides being thoroughly effective and reliable for its purpose.

A further object is to overcome numerous 25 disadvantages and objections frequently encountered in the use of many other contrivances hitherto devised with like ends in view.

The above and additional objects are attained by means substantially such as are 30 illustrated in the accompanying drawings, forming a part of this specification, in which like reference characters indicate like parts in all the views, and in which—

Figure 1 is a view in perspective of a paper 35 or pasteboard box having my improvements embodied in connection therewith, and Fig. 2 is an enlarged sectional plan view showing 40 certain features of the improvements.

Before proceeding with a more detailed 45 description it may be stated that my improvements are especially adapted to pasteboard and paper boxes of rectangular structure, and in the form of my improvements herein shown I employ specially-constructed opening devices for the box which normally may be also utilized as bails or handles for carrying the box when filled, said devices being 50 so organized with reference to opposite sides of the box as to enable said sides to be torn or severed from the remaining sides of the box in such manner as to enable the contents of the box to be removed in intact

form. While I have herein represented my 55 improvements in a certain preferred embodiment, it will be understood, of course, that I am not limited thereto in precise detail, since immaterial changes therein may be resorted to coming within the scope of 60 my invention.

Reference being had to the drawings by the designating characters marked thereon, 1 represents an ordinary paper or pasteboard box—such, for instance, as is frequently employed for containing ice-cream or other substances in bulk and which is provided with four sides 1, 2, 3, and 4, uniting with each other angularly, as indicated at 5, thus constituting the four corners of the box. Said 65 box may be provided with any suitable form of lid or closure, (indicated at 6,) and in order to enable opposite sides of the box to be severed or disconnected from the remaining sides thereof, by which the contents of the 70 box may be removed intact or unbroken in any part thereof, I provide at the corners formed by the four sides of the box suitable devices by which the said opposite sides of 75 the box may be torn away from the remaining parts of the structure. These devices are preferably in duplicate, and each consists of a wire or cord 7, extending within one of the corners of the box, as indicated at 8, thence passing through the bottom of the 80 box at 9 and extending across the bottom for its full width at 10, thence passing upwardly through the bottom at 11, and extending upwardly within the opposite corner of the box at 12 and outwardly at 13, the upwardly-projecting portion 14 of the wire forming a bail or handle by which the box 85 and its contents may be conveniently carried in the hand. The material of the wire of each of the devices may be such as not to 90 have any contaminating effect upon the contents of the box; but to absolutely guard against any contamination thereof I provide (preferably located in the corners of the box) 95 suitable paper or other strips 15, by which 100 the portions of the wire running interiorly of the box are completely covered and prevented from direct contact with the ice-cream or other commodity with which the box may be filled. Whenever it is desired to open the 105 box, it is simply necessary to first grasp the bail 14 of one of the devices with one hand, while holding the box with the other, and

then by pulling outwardly upon said bail the side of the box with which this particular device co-operates will be torn away from the sides intersecting therewith, substantially as indicated in dotted lines in Fig. 1. Then the bail 14 of the device located at the opposite side of the box is similarly operated to tear asunder the opposite side, whereupon after the opposite sides of the box have been torn away for their full height the remaining opposite sides of the box may then be turned downwardly flatwise upon the table or other support upon which the operations may be carried out, so that in this way the brick or block of ice-cream contained in the box may be removed in its complete or intact form. The ends of the wire of each of the devices described may be united in any suitable way, as by twisting at 16; and it will be seen that the portion 10 of each device extending across the bottom of the box furnishes a substantial leverage for the device in the operation thereof just described.

From the foregoing it is thought that the construction and operation of my improvements will be fully understood and also that the many advantages thereof will be apparent without further detailed description.

Having thus described my invention, I claim as new and desire to secure by Letters 30 Patent—

1. A rectangular box provided in each pair of opposite corners thereof with a wire extending along the corners of each pair, thence through and across the under side of the bottom of the box, the extremities of each of said wires being united above the top of the box to form a bail for the box. 35

2. A rectangular box provided in each pair of opposite corners thereof with a wire extending along the corners of each pair, thence through and across the under side of the bottom of the box, the extremities of each of said wires being united above the top of the box to form a bail for the box, and each corner of the box being provided interiorly with a shield for the corresponding inner portion of the wire, to prevent contamination of the contents of the box. 40

In testimony whereof I have signed my name to this specification in the presence of two subscribing witnesses.

CARL GOLDMANN.
